ELECTRIC SWITCH

Filed Feb. 18, 1927

UNITED STATES PATENT OFFICE

CHESTER D. AINSWORTH, OF WOLLASTON, MASSACHUSETTS, ASSIGNOR TO CONDIT ELECTRICAL MANUFACTURING CORPORATION, OF SOUTH BOSTON, MASSACHUSETTS, A CORPORATION OF MASSACHUSETTS

ELECTRIC SWITCH

Application filed February 18, 1927. Serial No. 169,362.

This invention relates to electric switches of the oil type having stationary terminals and a movable bridge member.

An object of this invention is the provision of a bridge member having a large surface area compared with its cross sectional area to obtain relatively high heat radiation whereby the bridge member can carry relatively high values of current without excessive heating.

Another object of the invention is the improved construction of the auxiliary stationary and movable arcing members.

These and other objects, which might hereinafter appear, are attained in the embodiment of the invention herein shown and described.

Fig. 1 shows an oil switch embodying the present invention.

20 Fig. 2 is a side view of the stationary and movable switch members.

Fig. 3 is an end view of the switch members shown in Fig. 2.

Fig. 4 is a plan view of a stamped blank 25 from which the bridge member is formed.

Fig. 5 is a side view of the bridge member formed from the blank shown in Fig. 4.

Fig. 6 is a perspective view of the bridge member formed from the blank shown in 30 Fig. 4.

As here shown, a switch casing 10 is provided with oil immersed stationary contact terminals 11 and 12 having main current-carrying members comprising inverted brush-members 13 and 14, a bridge member 15 secured to the operating rod 16, and co-operating auxiliary contact, or arcing members 17, 18 and 19, 20.

The bridge member 15 is formed from a 40 stamped blank of copper 15' of substantially the shape shown in Fig. 4 by bending the blank along the dotted lines *a* and otherwise shaping the blank to provide the channel-construction shown in Fig. 6 which comprises a broad and flat contact section 15^a having an aperture 15^b in the middle thereof and depending sections or sides 15^c and 15^d having inwardly directed end extensions 15^e and 15^f. These end extensions, at the tops thereof, 50 have horizontally disposed inwardly di-

rected apertured ears 15^g and 15^h to which the arcing members 18 and 20 are adapted to be secured.

The sides 15^c and 15^d and the intermediate flat contact section 15^a have a relatively great 55 heat-dissipating surface for a relatively small cross-sectional area, as compared with the usual bridge member, whereby to provide a high current-carrying capacity for a relatively small mass of copper. The sides 15^c and 15^d impart rigidity to the bridge member and increase the current carrying capacity and heat radiating surface of the bridge member making unnecessary a comparatively massive contact section.

The bridge member 15 is mounted on the reduced portion 16' of the insulating operating rod 16 and can rock slightly thereon in a vertical direction for the purpose of seating upon the brush members but is held from rotation on said rod. For this purpose, a plate 21 is positioned between the sides 15^c and 15^d and is rigidly secured to the shouldered end 16^a of the operating rod 16.

The construction of the arcing members 17, 18 and 19, 20 is best shown in Fig. 3. The arcing member 17 is a substantially U-shaped resilient integral strip secured to the contact terminal by screws 17' and preferably provided with arcing tips 17^a and 17^b. The arcing member 19 is of the same construction. The movable arcing member 18, cooperating with the arcing member 17, is of general inverted W-shape and comprises an integral strip of metal having an intermediate section 18^a which is secured to the apertured ear 15^g of the bridge member 15, and depending outwardly directed contact sections 18^b and 18^c formed with bends 18^d and 18^e which 80 impart a slight resiliency thereto. The movable auxiliary arcing member 20 that cooperates with the arcing member 19 is of the same construction as the arcing member 18. The members 17, 18 and 19, 20, thus constructed 85 cooperate in a comparatively long wiping action therebetween.

The construction and arrangement of parts may be modified without departing from the spirit of the invention.

I claim:

1. In an electric switch, the combination of stationary switch members comprising spaced brush members, and a movable bridging member comprising a stamping consisting of a flat plate of uniform thickness having opposed and downwardly reflexed sides forming with the body of the plate, a channel member, the body of said plate between said reflexed sides presenting a continuously flat upper face providing a contact face for said brush members.
2. In an electric switch, a movable bridging member characterized by being formed from a single piece of sheet metal reflexed to provide integral opposed depending side walls and an integral top connecting wall which has a continuously flat contacting upper face from end to end.
3. In an oil switch, a bridge member consisting of an inverted channel having a flat upper contact section, spaced depending integral walls, and arcing members located at and spaced away from the ends of said channel, the space within and below and at the sides of the channel being clear and unobstructed to permit free flow of a cooling medium.
4. In an oil switch, a bridge member having a middle contact section and depending sides having integral arcing-member supporting-extensions which are extended transversely of the middle section.
5. In an oil switch, a bridge member comprising an integral stamping consisting of a flat plate of uniform thickness reflexed to provide, as integral parts, a middle contact section, depending sides, and extensions integral with said sides adapted to carry auxiliary contact members.
6. A bridging member for an electric switch comprising a flat plate having integral depending side-members provided with oppositely-directed end-extensions having oppositely-directed laterally-reflexed ears providing seats for contact-members.
7. In an oil switch, stationary terminals, a movable bridge member cooperating therewith and comprising a middle contact section and depending sides, an operating rod on which said bridge member is mounted, and means to prevent rotary movement of said bridge member on said rod including means fixed to said rod and disposed between and having opposed faces parallel with and loosely engageable with said depending sides on opposite sides of said rod.
8. In an oil switch, an auxiliary arcing member comprising an integral U-shaped resilient strip arranged to be secured to a support at the middle of the strip and having free depending contact arms.
9. In an oil switch, an auxiliary arcing member comprising an integral U-shaped
- resilient strip and arcing tips fixed to the ends of said strip.
10. In an oil switch, an auxiliary arcing member comprising a single member having integral depending side contact sections having bends therein intermediate the contact sections for imparting resiliency thereto.
11. In an oil switch, cooperating stationary and movable contact members, one of said members comprising an integral U-shaped resilient strip having arcing tips at the ends thereof, and the other contact member comprising a strip of general inverted W-shape having opposed contact sections adapted to be yieldingly engaged by said arcing tips.
12. In an oil switch, cooperating stationary and movable contact members, one of said members comprising an integral U-shaped resilient strip including a bottom connecting portion and depending end portions having arcing tips at the ends thereof, said member being supported intermediate its bottom connecting portion, and the other contact member having integral opposed depending contact sections having bends therein for imparting resiliency thereto, said contacts having a yielding wiping action on each other.
- In testimony whereof, I have signed my name to this specification.
- CHESTER D. AINSWORTH.
